CONTROL FOR TWO-TEMPERATURE RE-
FRIGERATORS

Fred A. Harshberger, Springfield, Mass., assignor
to Westinghouse Electric & Manufacturing
Company, East Pittsburgh, Pa., a corporation
of Pennsylvania

Application September 29, 1936, Serial No. 103,104

7 Claims. (Cl. 62—116)

My invention relates to apparatus for controlling the operation of a refrigerating system having relatively high and low temperature evaporators and it has for an object to provide improved apparatus of this character.

A further object of my invention is to normally effect refrigeration of one of the evaporators of a multiple evaporator system, in preference to the other evaporator, when both demand cooling, and to transfer refrigeration to said other evaporator when its temperature increases to an abnormally high value.

In practicing my invention, I provide relatively high and low temperature evaporators connected to a common condensing unit and disposed for cooling the air in first and second zones of a refrigerator. Means is provided for effecting refrigeration of the evaporators, selectively, and temperature responsive elements associated with the respective zones of the refrigerator select the evaporator to be operated.

During normal operation, the condensing unit is operated with the high temperature evaporator in response to a demand for cooling from the high temperature zone and, conversely, the lower temperature evaporator is operated with the condensing unit in response to a demand for cooling from the low temperature zone. In the event of a demand for cooling from both of the refrigerated zones, one of the evaporators, such as, for example, the low temperature evaporator is given preference. At such times, the higher temperature zone is not being refrigerated and may rise in temperature to an abnormally high and undesirable value. Means is provided for transferring refrigeration to the higher temperature element when the temperature of the higher temperature zone rises to a predetermined abnormal value. When said abnormal temperature has been depressed to a predetermined value, normal control over the evaporators is re-established with the lower temperature zone having preference over the higher temperature zone.

The foregoing and other objects are effected by my invention as will be apparent from the following description and claims taken in connection with the accompanying drawing forming a part of this application, in which:

The single figure of the drawing shows diagrammatically a two-temperature refrigerator having my improved control apparatus applied thereto.

Referring to the drawing, I show a two-temperature refrigerator generally indicated at 10, and including relatively high and low tempera-

ture chambers 11 and 12, respectively. Evaporators 13 and 14 are disposed within the chambers 11 and 12, respectively, for abstracting heat therefrom. The high temperature evaporator 13 operates, primarily, to cool articles of food stored in the chamber 11 and the low temperature evaporator 14 operates to congeal fluid within containers shown at 14a and to maintain the temperature of the air in the chamber 12 at a relatively low value. Articles to be maintained in a frozen condition or at a low temperature are stored in chamber 12 as is well understood.

The evaporators 13 and 14 define elements of a refrigerating system having a common condensing unit 15, preferably of the compression type. The latter may include a hermetically sealed compressor (not shown) disposed within a hermetic casing 16 and driven by a motor, a winding of which is shown at 20, and disposed within the casing 16. As a hermetically sealed motor driven compressor of the type shown is well known in the art, no further description of it is deemed necessary. The terminals of the motor are shown at 17 and 17a. The condensing unit 15 includes a condenser 18 cooled in any suitable manner as, by a fan 19, and receiving compressed refrigerant gas from the compressor through a conduit 21.

Liquid refrigerant is conveyed to the evaporators 13 and 14 through a branched conduit 22 and vaporized refrigerant is withdrawn from the evaporators 13 and 14 through conduits 23 and 24, respectively. The refrigerating system which I have shown is of the well known flooded evaporator type having low side floats shown at 25 and 26 for controlling the admission of condensed refrigerant to the evaporators 13 and 14, in accordance with the levels of the liquid therein. A valve structure generally shown at 27 communicates with the suction conduits 23 and 24, and with the suction side of the compressor by means of a conduit 28. The valve structure 27 is selectively operated to effect communication between the conduit 28 and either conduit 23 and 24 depending upon which evaporator is being refrigerated.

As shown, the valve structure 27 includes inlet chambers 31 and 32 to which the suction conduits 23 and 24 are connected, and an outlet chamber 33 communicating with the suction conduit 28 of the compressor. Valve members 34 and 35 control communication between the chamber 31 or 32 and the outlet chamber 33. A solenoid 36 actuates the valve members 34 and 35 and, when energized, effects communication be-

50

55

tween the conduits 23 and 28 whereby the evaporator 13 is rendered active. When deenergized, the solenoid 36 connects the conduits 24 and 28 so that the evaporator 14 is active.

5 During operation of the condensing unit 15, vaporized refrigerant is withdrawn by the compressor from either evaporator 13 or 14 through conduit 28 depending upon whether the solenoid 36 is energized or deenergized. The withdrawn 10 gas is compressed to a relatively high pressure in the condenser 18 and is cooled and condensed. Liquid refrigerant is admitted to the evaporators 13 and 14 through their associated float valves 25 and 26 and is maintained at a substantially constant level in the evaporators. The compressor 15 maintains the pressure of the refrigerant in the evaporator at a relatively low value so that the refrigerant vaporizes at low temperature and abstracts heat from the evaporators in a well known 20 manner.

The foregoing defines a conventional refrigerating system having a pair of flooded evaporators operating at different temperatures and connected to a common condensing unit in such 25 manner that they are selectively operated. My improved control apparatus will now be applied to this system. It is to be understood that the system disclosed is shown by way of example and that my improved control apparatus may be 30 applied to other two-temperature systems having either flooded or so-called dry type evaporators with means for effecting vaporization in the evaporators, selectively.

The chamber 11, cooled by the high temperature 35 evaporator 13, is maintained between predetermined temperature limits preferably by means of a gas-type thermostat, generally indicated at 38. The thermostat 38 includes an expansible bellows 39 connected to a bulb 41 by 40 means of a tube 42. As is well understood, thermostats of this type have a volatile fluid contained in the bulb 41, the pressure of which is a function of the temperature of the bulb. Accordingly, the bellows 39 expands and contracts 45 as the evaporator 13 and bulb 41 increase and decrease in temperature, respectively. In this connection, it will be understood that the thermostat 38 may be made responsive to the temperature of the air in the chamber 11 instead of 50 the temperature of the evaporator 13 by disposing the bulb 41 in the air within the chamber 11.

Expansion of the bellows 39 is opposed by a 55 spring 43 which may be adjustable for varying the temperature at which the thermostat operates. A lever 44 pivoted at 45 is actuated by the bellows and carries movable contact members 46 and 47 forming parts of switch structures 48 and 49 respectively. The switches 48 and 49 include stationary contacts 51 and 52, respectively.

60 The operation of the switch 48 is such that the contacts 46 and 51 close and open to initiate and terminate operation of the condensing unit 15 in response to predetermined high and low temperatures of the evaporator 13, respectively. The 65 periods of operation when the temperature of the evaporator 13 is between these limits may be called normal operating periods, during which the movable and stationary contacts 47 and 52 of switch 49 remain in engagement. As shown, 70 this is accomplished by making the movable contact 47 of such length that it continuously engages the stationary contact 52 regardless of normal amplitudes of the bellows. However, during an abnormal operation, or when the temperature 75 of the evaporator 13 increases to an

abnormally high value, the movable contact 47 is disengaged from the stationary contact 52 due to the increased amplitude of the bellows 39. The purpose of this operation of the switch 49 will be made apparent hereinafter.

The temperature of the evaporator 14 and chamber 12 is controlled by a thermostat 53, preferably of the gas type. The thermostat 53 includes a bulb 54 which may be secured to the evaporator 14 and connected to a bellows 55 by 10 a tube 56. A lever 57, pivoted at 58, is actuated by the bellows 55 and carries a bridging contact 59 forming the movable member of a switch 61. The latter includes stationary contacts 62 which are bridged by the member 59 as the temperature of the evaporator 14 increases to a predetermined value. The contacts 59 and 62 are disengaged as the temperature of the evaporator is depressed to the desired value. The thermostat 53 may include an adjustable spring in opposition to the bellows, whereby the temperatures at which the switch operates may be varied. The switch 61 controls operation of the condensing unit 15 and, therefore, refrigeration of the evaporator 14.

20 Electrical energy for the motor of the condensing unit 15 is obtained from line conductors L₁—L₂ under control of the switches 48, 49, and 61. As shown, the switches 49 and 61 are connected in series in a conductor 65 extending from 30 the line conductor L₁ to the terminal 17 of the motor. The opposite terminal 17a of the motor is connected to the line conductor L₂. A conductor 66 controlled by the switch 48 extends from the line conductor L₁ to the motor terminal 35 17 and includes the solenoid 36.

25 It will be apparent from the foregoing that the motor of the condensing unit may be energized by two circuits, one of which includes the conductor 65 and the switches 49 and 61 and the other of which includes the conductor 66, the switch 48 and the solenoid 36.

Operation

In the position of the apparatus shown in the drawing, the condensing unit 15 is inactive as the temperature of the evaporators 13 and 14 are below the values at which the thermostats 38 and 53 operate to energize the motor winding 20. Assume that the temperature of the evaporator 14 rises sufficiently to close the switch 61 of the thermostat 53. The winding 20 of the motor is energized through a circuit including line conductor L₁, conductor 65, closed switches 61 and 49, winding 20, and line conductor L₂. The solenoid 36 is deenergized so that the evaporator suction conduit 24 communicates with the suction conduit 28 of the condensing unit 15 and, therefore, the evaporator 14 is refrigerated. The thermostat 53 opens the switch 61 in response to a predetermined low temperature of the evaporator 14 whereby the motor winding 20 is deenergized and refrigeration of the evaporator 14 is terminated.

In response to a predetermined high temperature of the evaporator 13, the thermostat 38 operates to close the switch 48 and, therefore, effect energization of the solenoid 36 and motor winding 20 through a circuit including line conductor L₁, the conductor 66 which has the solenoid 36 and closed switch 48 connected therein, motor winding 20 and line conductor L₂. Accordingly, the valve structure is actuated to its upper position so that the suction conduits 23 and 28 are communicating. Operation of the 75

condensing unit is initiated and refrigeration of the high temperature evaporator 13 is effected. The condensing unit operates until the temperature of the evaporator 13 is depressed to a pre-determined minimum value at which the thermostat 58 opens the switch 48 and effects deenergization of the motor winding 20 and the solenoid 36. Circulation of refrigerant ceases and the valve structure 27 is returned to the position shown in the drawing.

5 The various control instrumentalities are shown in their simplest form for the sake of clearness and it is to be understood that various other forms of instruments per se, which preferably include quick operating switch members, may be employed in my improved system.

10 I have disclosed a refrigerator having two separate compartments cooled by respective evaporators, but it will be understood that a refrigerator, having different zones of a single compartment cooled by separate evaporators, may be satisfactorily controlled by my improved control.

15 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

20 What I claim is:

25 1. In refrigerating apparatus, the combination of a refrigerator cabinet embodying different zones to be refrigerated, means for obtaining different refrigerating temperatures in said different zones of the refrigerator cabinet, means for effecting refrigeration of one of said zones in preference to another of said zones during normal temperature variations in said respective zones, and means for effecting refrigeration of said other zone in preference to said one zone when the temperature in said other zone rises abnormally.

30 2. In a control system for a refrigerator having relatively high and low temperature cooling compartments, the combination of means for selectively effecting refrigeration of the high and low temperature cooling compartments, and temperature responsive means associated with said compartments for controlling the operation of the refrigerating means and normally active to effect refrigeration of one of said compartments in preference to the other when both require cooling, said temperature responsive means including means for effecting refrigeration of said other compartment in preference to said one compartment when the temperature of the other compartment rises to an abnormally high value.

35 3. In a control system for refrigerating apparatus, the combination of a structure defining first and second cooling chambers, first and second cooling elements disposed for cooling the chambers, respectively, means responsive to a predetermined high temperature prevailing within the first compartment for effecting circulation of refrigerant through its respective element, means responsive to a predetermined high temperature obtaining within the second compartment for effecting circulation of refrigerant through its respective element, said temperature responsive means being so arranged that circulation of refrigerant is effected in the second element in preference to the first when the temperatures prevailing in both compartments are above said predetermined values, said temperature responsive means associated with the first compartment including means actuated in response to an abnormally high temperature prevailing within the first compartment for effecting circulation of refrigerant through its asso-

ciated element and for terminating circulation of refrigerant through the element of the second compartment.

4. In a control system for refrigerating apparatus having first and second cooling chambers, first and second evaporators disposed, respectively, in the chambers for cooling the same, means for condensing refrigerant for vaporization in the evaporators, means responsive to a predetermined temperature prevailing in the first chamber for effecting vaporization of refrigerant in its respective evaporator, means responsive to a second predetermined temperature prevailing in the second chamber for effecting vaporization of refrigerant in its respective evaporator, said temperature responsive means being so arranged that vaporization of refrigerant is effected in the second evaporator in preference to the first when the temperatures prevailing in both chambers are above said predetermined values, and a device actuated by said first temperature responsive means in response to an abnormal temperature, higher in value than said first predetermined temperature, for rendering the second temperature responsive means inactive, whereby vaporization of refrigerant is initiated in the first evaporator and terminated in the second, said device rendering the second temperature responsive means active when said abnormal temperature has been depressed to a normal value.
5. In a control system for a refrigerator having relatively high and low temperature cooling chambers formed therein, the combination of first and second evaporators for cooling the air in said chambers, respectively, means for translating refrigerant to the evaporators and selectively effecting vaporization therein, means responsive to temperatures prevailing within the respective chambers for controlling said refrigerant translating means, said temperature responsive means being so arranged that refrigerant is translated for vaporization in one of the evaporators in preference to the other when the temperatures obtaining within both chambers are above values which call for cooling thereof, and means associated with the temperature responsive means for effecting translation of refrigerant to said other evaporator for vaporization therein and for terminating vaporization of refrigerant in said one evaporator when the temperature obtaining in the chamber cooled by said other evaporator increases to a predetermined value.

6. In a control system for refrigerating apparatus having first and second cooling chambers, first and second evaporators disposed, respectively, in the chambers for cooling the same, means for condensing refrigerant for vaporization in the evaporators, a mechanism movable to first and second positions wherein refrigerant is delivered for vaporization in the first and second evaporators, respectively, means responsive to a predetermined temperature within the first compartment for actuating said mechanism to the first position, means responsive to a predetermined temperature within the second compartment for positioning the mechanism in its second position independently of the first temperature responsive means, and means responsive to an abnormal temperature within said first compartment higher than said first mentioned predetermined temperature, for rendering said second temperature responsive means inactive to control said mechanism, whereby refrigerant is delivered for vaporization in the first evaporator during periods when the abnormal temperature prevails and independently of the second temperature responsive means.

7. The combination of a cabinet structure having first and second chambers formed therein, first and second evaporators for cooling the chambers, respectively, means for condensing refrigerant for the evaporators, a device movable to first and second positions for effecting vaporization of refrigerant in the first and second evaporators, respectively, said device being biased to its second position and having a solenoid for actuating it to its first position when energized, means responsive to a predetermined temperature within the first chamber for energizing said solenoid and for effecting operation of the refrigerant condensing means, means responsive to a predetermined temperature within the second chamber for effecting operation of said refrigerant condensing means and for rendering said solenoid incapable of energization and means responsive to an abnormal temperature obtaining within the first compartment, which temperature is higher than said first predetermined temperature, for effecting operation of the refrigerant condensing means and for rendering the second temperature responsive means inactive.

FRED A. HARSHBERGER.
